(57) **CLAIM**

The ornamental design for a display screen or portion thereof with animated graphical user interface, as shown and described.

DESCRIPTION

FIG. 1 is a front view of a display screen or portion thereof with animated graphical user interface, showing a first image of the new design.

FIG. 2 is a second image thereof.

FIG. 3 is a third image thereof.

FIG. 4 is a fourth image thereof.

FIG. 5 is a fifth image thereof.

FIG. 6 is a sixth image thereof.

FIG. 7 is a seventh image thereof.

FIG. 8 is an eighth image thereof.

FIG. 9 is a ninth image thereof.

FIG. 10 is a tenth image thereof.

FIG. 11 is a front view of a display screen or portion thereof with animated graphical user interface, showing a first image of a second embodiment of the new design.

FIG. 12 is a second image thereof.

FIG. 13 is a third image thereof.

FIG. 14 is a fourth image thereof.

FIG. 15 is a fifth image thereof.

FIG. 16 is a sixth image thereof.

FIG. 17 is a seventh image thereof.

FIG. 18 is an eighth image thereof.

FIG. 19 is a ninth image thereof; and,

FIG. 20 is a tenth image thereof.

The appearance of the animated image sequentially transitions between the images shown in FIGS. 1 through 10 and FIGS. 11 through 20, respectively. The process or period in which one image transitions to another image forms no part of the claimed design.

The outermost broken lines in the figures show a display screen or portion thereof, and form no part of the claimed
